CHARLES T. HARVEY, OF TARRYTOWN, NEW YORK.

Letters Patent No. 99,435, dated February 1, 1870.

IMPROVED SUPPORTING-COLUMN FOR ELEVATED RAILWAYS.

The Schedule referred to in these Letters Patent and making part of the same.

To all whom it may concern:

Be it known that I, CHARLES T. HARVEY, of Tarrytown, in the county of Westchester, State of New York, have invented a new and useful Improvement in Supporting-Columns for Elevated Railroads; and I do hereby declare the following to be a full, clear, and exact description thereof, which will enable those skilled in the art to make and use the same, reference being had to the accompanying drawing, forming part of this specification, in which drawing—

Figure 1 represents a sectional front view of this invention.

Figure 2 is a transverse section of the same.

Figure 3 is a horizontal section of the same.

Similar letters indicate corresponding parts.

This invention relates to a novel construction of column, intended principally for supporting the track of an elevated railroad.

In the drawing—

The letter A designates a column, which is composed of two (or more) solid wrought-iron rods, a, which are secured in sockets b, in the base-plate B.

This base-plate is, by preference, made of cast-iron, and it is provided with two bosses, of considerable height, which are bored or cored out to form the sockets b, and by these means, sockets of sufficient depth are obtained, to render the position of the rods a firm and steady.

The bosses b are connected by a rib, c, which materially, increases the firmness of the said bosses, and also the stiffness and supporting-power of the base-plate B.

The rods a are either made of round, square, or polygonal iron, or they may be constructed, each, of two or more flanged pieces of sheet-metal or rolled-iron, and they can be secured in their sockets, by casting lead around their lower ends; but I prefer to secure them therein by means of keys, d, which allow of raising or depressing either of the rods, for the purpose of levelling the top of the column independently of the position of the base-plate. The rods can be raised by placing flat rings or disks in the bottoms of the sockets, so as to lessen their depth, and thereby limit the extent to which the rods are allowed to sink down in them.

The sockets b are slightly converging, so that the rods a, on being secured in said sockets, incline inward, as shown in fig. 1, and the upper ends of the rods are curved outward, so that they form a bearing, of sufficient width for the railroad track.

The rails are secured to a frame, C, which is fastened to the top ends of the rods a, and, in order to obtain good bearings for said frame, and to connect the top of my improved column thereto securely, I provide the under side of the frame with bosses, F, which are bored or cored out to form sockets, h, to receive and confine the flaring upper ends of the rods a, substantially in the same manner as the lower ends of the rods, the rods and sockets being keyed or secured to each other, in any suitable manner. Said frame also assists in strengthening the column, since by it, the rods a are firmly united.

To increase the strength and stability of my column, I connect the rods a, composing such column, by straps e f, and cross-brace g, one of the straps being applied to those parts of the rods which are closest together, while another strap embraces the flaring ends of said rods, and is connected to the first strap by the braces g, as shown in fig. 1. As many straps are used as are necessary for security.

Between the rods a, and at suitable distance from the ground, may be fastened a lantern, D, and a mailbox, E.

By these means, a very firm, durable, and strong column can be made, which, on account of its comparatively light weight, can be made at much less cost than a solid or tubular column of equal strength.

Having thus described my invention,

What I claim as new, and desire to secure by Letters Patent, is—

1. A supporting-column, constructed of two or more solid rods, a, secured in sockets b of the base-plate B, substantially as described.

2. The arrangement, of the sockets h, on the under side of the rail-frame C, in combination with the rods composing the column, substantially as set forth.

3. The combination of braces g and fastening of straps e f, or equivalents, with a supporting-column, A, substantially as described.

4. The employment of rings or equivalent devices, in connection with the base-plate B b, and rods a a, for the purpose of levelling said rod, as set forth.

This specification signed this 24th day of May, 1869.

CHARLES T. HARVEY.
